TOOTHBRUSH POWER HANDLE OR SIMILAR ARTICLE

George H. Fitzsimonds, Trumbull, Conn., assignor to General Electric Company, a corporation of New York

Filed May 21, 1962, Ser. No. 70,210

Term of patent 14 years

(Cl. D9—2)

FIG. 1 is a front perspective view of a toothbrush power handle embodying my new design;

FIG. 2 is a front elevational view of the toothbrush power handle shown in FIG. 1;

FIG. 3 is a top plan view of the toothbrush power handle shown in FIG. 1; and

FIG. 4 is a bottom plan view of the toothbrush power handle shown in FIG. 1.

I claim:

The ornamental design for a toothbrush power handle or similar article, substantially as shown.
